CLAIM

The ornamental design for a stretch slipcover for reclining loveseat, as shown and described.

DESCRIPTION

FIG. 1 is a perspective view of a stretch slipcover for reclining loveseat showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof showing the stretch slipcover for reclining loveseat of FIG. 1 in a reclining position.

The broken lines in the drawings depict portions of the stretch slipcover for reclining loveseat that form no part of the claimed design.

1 Claim, 8 Drawing Sheets
